2,667,772

AUXILIARY YARN TENSIONING MEANS

Carlos A. Hepp, Englewood, N. J., assignor to
Alfred Hofmann & Co., West New York, N. J.,
a corporation

Application August 14, 1951; Serial No. 241,832

9 Claims. (Cl. 66—146)

1

This invention relates to auxiliary yarn tensioning means for warp knitting machines.

The problem of yarn tensioning in warp knitting machines such as the high speed tricot and Simplex types, has been considered at length and a number of patents have been granted in this field including 2,394,161; 2,395,807; 2,397,663 and 2,521,218; all assigned to the assignee of the instant application. Such patents are primarily directed to improvements in the control of the yarn supply through means for driving and braking the reel shafts which carry the yarn reels, so as to control the flow of yarn in accordance with the knitting requirement.

More particularly, machines described in the above mentioned patents include a yarn guide rod mounted on rock arms which are resiliently urged in one direction by suitable spring means, the sheet of yarns moving over the guide rod to the knitting elements and being tensioned during the knitting operation by the spring means, in conjunction with braking means actuated for controlling the rotation of the reel shaft.

It has been found however, that with such arrangements, the quality of the knitted fabric is variable due to variations in yarn tension, despite the provisions for tensioning the yarns as described above. Obviously, the yarn guide rod is compelled to follow certain motions of the knitting elements, which are in no way related to the determination of the yarn flow requirement. As a result, the up and down movement of the yarn guide rod, particularly in high speed machines, produces excessive motions which are transmitted to the yarns, causing the same to flutter in their passage between the guide rod and the knitting elements. In addition, excessive guide rod motion may frequently be responsible for yarn breakage due to a resultant jerking action in respect to the yarns.

Accordingly, an object of this invention is to provide in warp knitting machines having conventional resilient yarn tensioning means, auxiliary yarn tensioning means adapted to substantially reduce the up and down motion of the main yarn tensioning means and thereby materially reduce the fluttering and jerking of the yarns.

A further object of this invention is to provide auxiliary yarn tensioning means which may be readily attached to conventional warp knitting machines without material modification of the same, yet adapted for operation with the main

2

yarn tensioning means of the machine, whereby to render more effective the usual braking devices associated with the yarn reels or the combination braking and yarn reel drive mechanisms found in such machines.

Another object of this invention is to provide in warp knitting machines, auxiliary yarn tensioning means adapted to be located in a position such that the normal flow of yarn to the main yarn tensioning means is diverted, whereby the auxiliary tensioning means is adapted to become operative before the main yarn tensioning means during various phases of yarn movement to the knitting elements, thereby materially reducing the up and down movement of the main yarn tensioning means.

Other objects of this invention will in part be obvious and in part hereinafter pointed out.

The invention accordingly consists in the combination of elements and arrangement of parts which will be exemplified in the constructions hereinafter described.

In the drawings,

Fig. 1 is a side elevational view of the yarn tensioning means embodying the invention, with parts in section;

Fig. 2 is a top plan view thereof; and

Fig. 3 is a side elevational view of a yarn tensioning means embodying the invention and illustrating a modification thereof.

Referring in detail to the drawing, and particularly to Fig. 1, 10 designates a fulcrum bar or rockaxle of a conventional warp knitting machine, such bar extending longitudinally of the machine and suitably mounted in the frame of the machine, in a manner well known in the art. The bar 10 may also be arranged for rocking movement so as to provide means for actuating brakes or reel driving means, in a manner known in the art.

The main yarn tensioning means comprises a plurality of similar, suitably spaced arms 11 disposed at right angles to the bar 10 and suitably fixed at their inner ends to said bar. At the outer ends of the arms 11, there is fixed the longitudinally extending yarn guide tension bar 12 which is parallel to bar 10. On the opposite side of bar 10 is provided a longitudinally extending steady rod 13, suitably fixed on the frame of the machine and providing guide means for directing the sheet of yarn *y*, coming from the reel, not shown, to the guide bar 12, the yarns then moving downwardly to the knitting elements, not shown.

As in conventional warp knitting machines,

arms 11 and guide bar 12 are urged in an upward direction by suitably located spring means, in a manner known in the art and typically shown in Patent 2,521,218. Thus, the moving sheet of yarns are tensioned with the spring means contracting and expanding in accordance with the yarn demand of the knitting elements. It follows that the arms 11 and the guide bar 12 must execute repeated up and down movements in response to the variation in tension of the moving yarns and the rate of such movement is determined by the speed of the machine.

Means is provided for substantially reducing the up and down movement of the main yarn tensioning means. To this end there is provided auxiliary yarn guide tension means. Such auxiliary means comprises a plurality of similar, resilient elements 14. Each element 14, which may be made of thin, strip metal, includes an intermediate, preferably curved portion 15 which may be complementary to the curvature of bar 10 and is adapted to freely straddle the same. Extending from either side of portion 15, are upwardly inclined arm portions 16, 17. The resilient elements 14 are suitably spaced on bar 10 and have the outer ends of arm portions 16, 17, respectively interconnected by auxiliary guide rods 18, 19 which extend parallel to main guide bar 12. As shown in Fig. 1, the arm portions 16, 17 may be of equal length and shorter than arms 11. Furthermore, arm portions 16, 17 are inclined at an angle such that the auxiliary guide rods 18, 19 are normally located above the axis of the bars 10, 12.

It will be apparent from a consideration of Fig. 1, that the sheet of yarns y, which would normally travel in a path indicated by the dot and dash lines a, are now diverted to a new path indicated by the dotted lines b.

The spring elements 14 show a lesser resistance to a given force than the spring means, not shown, which urges the arms 11 upwardly. Accordingly, with normal operation of the knitting machine, take up in the slack of the yarns y moving to the knitting elements, will in a large part be accomplished by means of the auxiliary yarn guide tension means. In the event that yarn tension attains a value such that the arm portions 16, 17 are biased to a point where the rod 18 is in the same horizontal plane as the guide bar 12, then any increase in yarn tension beyond said value, will cause guide bar 12 to move downwardly. In such event, arms 11 will rock the bar 10 in a manner known in the art and may thus actuate brake means or reel driving means, as more specifically described in Patent 2,521,218.

It follows, that the up and down movement of the main yarn guide tensioning means will be materially reduced at all speeds of the knitting machine. Furthermore, it has been found that with the auxiliary yarn tensioning means, as shown herein, flutter of the yarns is greatly reduced and the brake and reel drive mechanisms which may be associated with the fulcrum bar 10, operate with greater efficiency.

In warp knitting machines having double yarn guide tension bars 12, 12a, mounted on oppositely extending arms 11, 11a, respectively, as shown in Fig. 3, the auxiliary yarn tensioning means comprises strip spring elements 14a. Such elements include an intermediate curved portion 15a which loosely straddles the underside of the bar 10 and is kept in place by straps 20. The arm portions 16a, 17a extend from either side

of portion 15a and are inclined downwardly. Guide rods 18a, 19a interconnect the outer ends of arm portions 16a, 17a, respectively. As shown in the figure, rods 18a, 19a are normally located in a horizontal plane below the horizontal plane containing guide bars 12, 12a. In this manner, the path of yarns y is again diverted or displaced from the normal whereby the spring elements 14a may function independently of the main yarn tensioning means until the main yarn tensioning means attains a given value when the main yarn tensioning means will operate as described above.

It will be apparent that the auxiliary yarn tensioning means described above, may be readily mounted on the fulcrum bar of a conventional warp knitting machine, or upon any other suitable support forming a part of the machine.

The resilient capacity of one or more of the spring elements 14, 14a, may be modified by varying the transverse section or longitudinal extent thereof. The guide rods 18, 19; 18a, 19a, may be of light, somewhat flexible material, so that the same may exhibit varying response to different yarn tensions along the length of the machine. Thus, the selvage portions of the machine may have reduced tension responses as compared to intermediate portions of the machine.

While the auxiliary yarn tensioning means described above includes resilient arm portions extending from either side of the fulcrum bar or other suitable support, it is understood that the auxiliary yarn tensioning means may have but single arm portions extending from one side only of the fulcrum bar or other suitable support. In such case, the arm portions may be fixed to the support.

As various possible embodiments might be made of the above described invention, and as various changes might be made in the embodiments set forth, it is understood that all matter herein set forth or shown in the drawings, is to be interpreted as illustrative and not in a limiting sense.

Having thus described my invention, I claim as new and desire to protect by Letters Patent:

1. In a warp knitting machine, the combination of a movable fulcrum member, a yarn guide tension bar on said movable member, and auxiliary yarn tensioning means mounted on said fulcrum member and including a resiliently mounted auxiliary yarn guide tension bar having an axis normally located in a plane parallel to a plane containing the axes of said movable member and first mentioned yarn guide tension bar, said auxiliary yarn guide bar being movable towards and away from said second mentioned plane.

2. In a warp knitting machine, a movable member, main yarn guide tensioning means including a guide bar mounted on said member, auxiliary yarn tensioning means comprising a plurality of similar, spaced resilient members, each member including an intermediate portion mounted on said movable member and a pair of oppositely disposed arm portions extending from said intermediate portion, said arm portions on at least one side of said movable member being interconnected by an auxiliary guide bar extending parallel to said first mentioned guide bar, said auxiliary guide bar being located in a horizontal plane spaced from and parallel to a horizontal plane containing said first mentioned guide bar.

3. In a warp knitting machine as in claim 2 wherein said auxiliary guide bar is located above

a horizontal plane containing said movable member.

4. In a warp knitting machine as in claim 2 wherein said auxiliary guide bar is located below a horizontal plane containing said movable member.

5. In a warp knitting machine, an elongated fulcrum support, main yarn guide tensioning means including a main guide bar extending parallel to and to one side of said support, auxiliary yarn guide tensioning means including an auxiliary guide bar located between said main guide bar and said support and parallel thereto, and resilient means for normally positioning said auxiliary guide bar to one side of a plane containing said main guide bar and support.

6. In a warp knitting machine as in claim 5, wherein said auxiliary guide bar is fixed to said support.

7. In a warp knitting machine as in claim 5 wherein said resilient means includes a plurality of members located in spaced relation, said members being of variable resilience.

8. In a warp knitting machine, a pair of adjacent movable yarn guide members, resilient means for mounting one of said members and operative in response to at least a predetermined yarn tension to move said one member, resilient means for mounting the other of said members and operative in response to yarn tensions less than said predetermined tension to move said other mem-

ber, said other member being movable in response to said predetermined yarn tension to a position relative to said one member whereby said pair of members are conjointly movable in response to said predetermined yarn tension.

9. In a warp knitting machine, a resiliently mounted movable member for guiding yarns in a predetermined path, a second resiliently mounted movable guide member adjacent said first mentioned member for displacing said yarns from said path in response to yarn tensions less than a predetermined tension, said second guide member being movable in response to said predetermined yarn tension to a position relative to said first mentioned member whereby said yarn is restored to said predetermined path, and said first and second members being conjointly movable in response to yarn tensions greater than said predetermined tension.

CARLOS A. HEPP.
